UNITED STATES PATENT OFFICE

JAMES W. BRYCE, OF BINGHAMTON, NEW YORK, ASSIGNOR TO THE INTERNATIONAL TIME RECORDING COMPANY OF NEW YORK, A CORPORATION OF NEW YORK.

SECONDARY CLOCK.

1,378,653.

Specification of Letters Patent. Patented May 17, 1921.

Application filed May 17, 1920. Serial No. 382,115.

To all whom it may concern:

Be it known that I, JAMES W. BRYCE, a citizen of the United States of America, residing at Binghamton, in the county of 5 Broome and State of New York, have invented certain new and useful Improvements in Secondary Clocks, of which the following is a full, clear, and exact description.

In numerous patents heretofore granted to 10 me I have shown and described a method and an apparatus for synchronizing clocks, now well known on the market as the C. T. R. or Bryce system, the more salient features of which, for purposes of this case, may be 15 generally described as follows:

The master clock sends to the line, with 20 which one or more secondary clocks are connected, a current for fifteen minutes, once every hour. Each secondary clock contains means which accelerate its rate, which retard its rate, or which permit it to run at its normal rate, and these means are brought 25 into the main or line circuit at definite intervals with reference to the time as indicated by the secondary, so that if the said clock be 30 too slow the accelerating means are rendered operative until the clock has caught up to the master clock, or if too fast it is stopped or retarded until the master clock has caught up to it.

In this system, as in others of its kind, experiments based on practical conditions of operation and use, have led to the development and adoption of a commercial form of 35 apparatus, which, while operating on the same principle, exhibits certain novel but specific structural features which have proved to be best adapted for accomplishing the objects of the invention, and this application is based upon an improved accelerating device for such final or finished form of 40 clock mechanism, and it resides in the features of construction which will be herein-after set forth and described.

45 In the accompanying drawings which illustrate this improvement:

Figure 1 is a diagram of the system in which the clock is used.

Fig. 2 is a view in elevation of the interior 50 of a complete clock embodying the improvement.

Fig. 3 is a detail of a ratchet and pawl device.

Figs. 4, 5 are details of the accelerating 55 devices.

So far as the master clock is concerned, the system herein described differs in no essential respects from those heretofore in use. For example, Fig. 1 shows in the upper portion of the sheet a typical form of 60 this device, in which 1 and 2 represent the mains of a circuit from any suitable source of supply. On the minute arbor 3 of the master clock is a contact 4, and cooperating with this contact is a contact 5 oscillated by 65 the balance shaft 6 so that an electrical connection is established once every minute.

On the hour shaft 7 is a disk 8 having two short conducting segments 9 and 10 in its periphery, upon which bear a pair of insulated 70 brushes 11. A local battery or other source of current 12 is by the means described closed momentarily at fifteen minutes intervals during each hour and thereby energizes an electro-magnet 13 which, operating 75 through a suitable ratchet mechanism, moves a ratchet wheel 14, step by step. One of a pair of contacts bears upon the teeth of this ratchet and when on a high point a tooth closes the main circuit, and when on a low 80 point breaks this circuit. The parts are so related that current is thus sent to line for exactly fifteen minutes every hour.

In each secondary clock, one of which is shown diagrammatically in the lower part 85 of the sheet, a cam disk 16 is mounted on the hour shaft, and upon its periphery bears the center member of three contacts 17. For fifteen minutes during each hour, secondary 90 clock time, the middle contact rests upon the high part of the cam 16, and the electromagnet 22, which controls the ratchet wheel 31, is brought into a branch of the main circuit. If the secondary clock be exactly on time, then the middle contact will drop off from 95 the high part of the cam at exactly fifteen minutes of the hour, true time, or at the instant when the master clock begins to send its fifteen minute impulse, and hence magnet 22 will receive no current, but if the 100 clock be slow, then the contact will reach the high part of the cam before fifteen minutes of the hour and will not drop off until after the master clock impulse has begun to flow; consequently, the clock will be speeded up 105 until the hands have reached the fifteen minute position.

When the middle contact drops off the high part of the cam it travels for fifteen 110 minutes on a neutral part of said cam 23.

If, therefore, the clock be fast, it will drop off the neutral part before the even hour, and falling upon the low part 24, brings the middle and lower contacts together whereby 5 the main current will be directed through magnet 18 which controls a brake 19 working on the balance wheel 20, and the clock therefore stops until the master clock catches up with it. After another short interval 10 the middle contact rises onto another neutral part of the cam disk 23.

The construction of the secondary is similar to those in use except, so far as the present case is concerned, in the accelerating device shown in Figs. 4, 5 and 6. The magnet 22 of this device operates to attract an armature 25, carried by a slab secured to a lever 26, pivoted at 27. Pivoted to this lever at 28 is a lever 29 which has a toe 30 that normally 20 engages with a ratchet wheel 31. The lever 26 has a bent over end 60 that engages the lever 29, and the latter has a stop 32 that engages the bent over end 60 of lever 29. Lever 26 has also a projection 33 that bears 25 upon the shaft of the ratchet 31 and acts as a limiting stop for said lever.

When magnet 22 is energized the toe 30 is thrown out of engagement with the ratchet 31 and the clock runs down rapidly until it 30 catches up with the master clock, as ratchet 31 is in gear with one side of the differential in the clock movement and when released has only a fan 34, Fig. 5, to oppose the running down of the train.

In other respects than those noted, the construction of the clock mechanism is, or 35 may be, of the usual and known character. As constructed and described the mechanism constituting the improvement of this application has been found well adapted to its 40 intended purpose, and represents the results of long conducted tests and experiments.

What I claim is—

1. In a secondary clock of the kind herein

described, the combination with the train of 45 an accelerating device, comprising an electromagnet, a pivoted armature lever therefor, a ratchet wheel, the shaft of which constitutes a fixed stop for a projection on said armature lever, a spring actuated pawl lever 50 pivoted to the armature lever and limited in its vibratory movement by a fixed stop thereon and normally engaging with the ratchet, a means, such as a fan wheel in gear with the clock train and under the control 55 of the ratchet, these parts being so constructed and arranged that upon a movement of the armature lever under the magnetizing influence of the magnet, the pawl lever is moved out of engagement with the ratchet, 60 but upon the cessation of magnetism and return of the said armature lever is moved back into engagement with the said ratchet.

2. In an accelerating device for secondary 65 clocks, the combination with an electromagnet, a pivoted armature lever, a lever pivoted thereto, a ratchet wheel, means for permitting the train to run at an accelerated rate controlled thereby, and means carried by the pivoted lever for engaging with the ratchet, 70 and a projection on the armature lever for engagement with a fixed part for limiting the play of said lever.

3. In an accelerating device for secondary 75 clocks, the combination of an electromagnet, a pivoted armature lever, a spring actuated lever pivoted thereto, a ratchet wheel, a fan wheel in gear with the clock train and controlled by the ratchet, means on the pivoted 80 lever for normally engaging with the ratchet wheel, and means on the armature lever for limiting its range of movement, the latter composed of a projection normally in contact with the shaft of the ratchet.

In testimony whereof I hereto affix my 85 signature.

JAMES W. BRYCE.
